OSCAR KLEINSCHMIT, OF LEIPZIG-PLAGWITZ, GERMANY, ASSIGNOR TO GEBRUDER BREHMER MASCHINEN-FABRIK, OF LEIPZIG-PLAGWITZ, GERMANY

PAPER FOLDING MACHINE

Application filed December 23, 1929, Serial No. 416,135, and in Germany October 14, 1929.

In paper folding machines and more particularly in machines employing buckling plates or guides for effecting one or more parallel folds in the paper sheet by the well known buckling process the sheets are fed either manually or on conveyor bands or tapes to the rollers which convey the same to the buckling plates. Before the sheets are seized by the rotating feed rollers the stack of sheets is usually brought up against a lateral guide or passed between two such guides that can be adjusted to allow for sheets of various sizes. These guides bearing on the edges of the sheets and the continuous feed are apt to throw the individual sheets out of alignment, when they are fed forward one at a time off the stack, which entails the provision of special means such as inclined conveyor tapes or rollers to ensure that the sheets pass to the folding mechanism in the correct position relatively to the longitudinal axis of the machine. This disadvantage is obviated according to the present invention by mounting one or both of the lateral guides in such a manner that it or they are moved away out of contact with the stack at the moment that a sheet is fed forward and are returned to their normal position only when the sheet has travelled clear of the lateral guides. In order however that the nature of the invention may be readily understood one method of carrying the same into effect is shown by way of example in the accompanying drawings in which similar reference characters relate to like parts throughout the several figures, and in which:—

Figure 1 is a side elevation of a folding machine of the type previously referred to. Figure 2 is a front elevation, partly in section, showing the lateral guides moved away out of contact with the stack of sheets, and

Figure 3 is a similar view showing both guides in their normal position.

Figure 4 is a plan view with the parts in the position shown in Figure 3.

Referring now to the drawings, which are of a somewhat diagrammatic nature showing only the parts which are essential to the proper understanding of the invention, it

will be appreciated that as is usual in this class of machines the stack of sheets *a*, prearranged to ensure the accurate feed of the individual sheets, is fed by means of conveyor tapes, running on the upper table *a'*, and thence around the drum *c* on to the table *b* and there passes between the two lateral guides *d* and *d'*.

The rotating feed rollers *e* and *f* rise and fall alternately in the well known manner to feed the individual sheets off the stack, the roller *e* withdrawing the individual sheets from the stack and passing the same between the rotating rollers *f* and *f'* by which they are fed on to the conveyor tapes *g* and carried against the adjustable registering grade *h* to the first pair of feed rollers *i* and *j* and from thence into the buckling plates or guides *k* for the usual buckle folding operation by the rollers *j* and *j'*.

According to the present invention means are provided for moving either the lateral guide *d'* or both lateral guides *d* and *d'* out of contact with the stack *a*. For this purpose the guide *d'* is mounted on the three bars or rails *l*, *m* and *n* that are adapted to slide in grooves *o* provided on the upper surface of the table *b* and the guide *d* is similarly mounted on the three bars or rails *l'*, *m'*, *n'*. In order to allow for sheets of various widths the position of the guides *d* and *d'* on these bars can be adjusted, each guide being formed for this purpose with three slotted lugs *q* whereby they can be secured in any desired position on the rails by means of the thumb screws *p*.

To one end of the central bar or rail *m* is attached the lever *u* that is pivotally mounted on the pin *v* carried by the bracket *v* fixed to one of the side frames *w* of the machine the other end of the lever *u* being provided with a roller *u'* that is kept in contact with the cam *x* mounted on the shaft *y* that is constantly rotated by any convenient means.

It will be clear that due to the rotation of the cam *x* the lever *u* will be oscillated on its pivot *v* so that a reciprocatory movement will be imparted to the bar *m*, whereby the lateral guide *d'* will be alternately moved out of contact and returned into contact with the

stack of sheets *a* and the several shafts are so geared together and the operation of the cam so timed that the guide *d'* is moved away at the precise moment when the uppermost sheet of the stack has been passed by the operation of the roller *e* to the rollers *f* and *f'*; the actual outward movement of the lateral guide taking place as the roller *f* swings downwardly in readiness to pass the sheet in co-operation with the roller *f'* to the conveyor tapes *g*.

It will also be clear that both guides *d* and *d'* may be simultaneously moved out of contact with the stack and returned to their normal position by the oscillation of the lever *u* operated by the cam *x*.

To effect this simultaneous movement of both the lateral guides *d'* and *d* a lever *s* is pivotally mounted on a bracket *r* secured to the under-surface of the table *b* and is connected at its opposite ends by pivoted links *t t'* to the pivot pins 10 and 11 depending respectively from the central bars *m m'*.

What I claim is:—

- 25 1. In a paper folding machine the combination with means for feeding a stack of paper sheets between two lateral guides, means for withdrawing single sheets successively from said stack and means for conveying same to the folding mechanism of means for moving both of said lateral guides out of contact and returning same into contact with said stack for the purpose specified.
- 30 2. In a paper folding machine the combination with means of feeding a stack of paper sheets between two lateral guides, a roller for withdrawing single sheets successively from said stack, a pair of co-operating rollers receiving said sheets from said first
- 35 40 roller and a conveyor receiving sheets from said pair of co-operating rollers and conveying same to the folding mechanism of means for moving one of said lateral guides out of contact with said stack at the moment when said pair of co-operating rollers come into operation and for returning said lateral guide to its original position into contact with the stack.
- 45 50 3. In a paper folding machine the combination with means for feeding a stack of paper sheets between two lateral guides, a roller for withdrawing single sheets successively from said stack, a pair of co-operating rollers receiving said sheets from said first
- 55 60 65 roller and a conveyor receiving sheets from said pair of co-operating rollers and conveying same to the folding mechanism of means for moving both of said lateral guides out of contact with said stack at the moment when said pair of co-operating rollers come into operation and for returning said lateral guides to their original position into contact with the stack.
